UNITED STATES PATENT OFFICE.

ERNST MARTIN HUGO LONITZ, OF NEUHALDENSLEBEN, PRUSSIA, GERMANY.

BOX FOR PACKING MONEY.

SPECIFICATION forming part of Letters Patent No. 379,966, dated March 27, 1888.

Application filed May 4, 1887. Serial No. 237,160. (No model.) Patented in Belgium March 1, 1887, No. 76,533; in England March 1, 1887, No. 3,176; in France March 1, 1887, No. 181,899; in Spain March 15, 1887, No. 10,708, and in Austria-Hungary July 6, 1887, No. 14,150 and No. 11,716.

To all whom it may concern:

Be it known that I, ERNST MARTIN HUGO LONITZ, a subject of the King of Prussia, Germany, residing at the city of Neuwaldensleben, 5 in the Kingdom of Prussia, Germany, have invented certain new and useful Improvements in Boxes for the Packing of Money, (for which I have obtained Letters Patent in Belgium, No. 76,533, dated March 1, 1887; in Great Britain, No. 3,176, dated March 1, 1887; in France, No. 181,899, March 1, 1887; in Austria-Hungary, No. 14,150 and No. 11,716, dated July 6, 1887; and in Spain, No. 10,708, dated March 15, 1887,) of which the following is a specification.

15 The object of this invention is a box or tube adapted to receive and hold a certain number of coins of one denomination. For this purpose the tubes have different diameters, according to the size of the coin to be packed, 20 and different height or length, according to the thickness of the respective coin. For instance, tubes for five-dollar pieces may have such a size as to contain exactly twenty five-dollar pieces, equaling one hundred dollars. 25 If, therefore, five-dollar pieces are to be packed, these tubes have only to be filled therewith, and it is known without counting the pieces that the tube contains one hundred dollars. Time is saved thereby in counting, and the 30 troublesome rolling up in paper and the sealing of the rolls is dispensed with.

Referring to the accompany drawings, Figure 1 shows the interior shell of the box filled with coins; Fig. 2, a section of the cover of 35 the said box; Fig. 3, an end view of the interior shell; Fig. 4, the box closed and fastened; Fig. 5, an adhesive capsule for the fastening of the said box.

The boxes consist, essentially, of two parts— 40 viz., a half-cylinder having two closed ends and a whole cylinder having one closed end only and serving as a cap or cover for the said half-cylinder.

A is the hollow half-cylinder, provided at 45 its extremities with fixed end plates, a' and a'' , and serving to receive the coins x . The outer plate, a' , is circular and has a slightly larger radius than the semi-cylinder A, while the inner plate, a'' , does not project beyond the outer 50 surface of the semi-cylinder A.

B is the hollow cylindrical cover, which is open in front and closed at one end by the plate b. This cylinder is shifted as a cover over the semi-cylinder A when filled with coin and holds the coin securely packed. 55

To take out the coins, the semi-cylinder A is pulled out of B, and the money may then be removed from the semi-cylinder A. While drawing out the part A the tube B should be held in such a position that the semi-cylinder 60 A lies below and so supports the coins. In order that the position of the part A may be recognizable when the box is closed, the tube B may be provided with a little hole, b' , through which the coin x or the semi-cylinder A can 65 be recognized.

For the purpose of closing the tube for conveyance I preferably employ an adhesive capsule, C, having a serrated or indented rim, Fig. 5. This capsule is pasted over the end 70 a' of the semi-cylinder A and its overstanding indented rim fastened down onto the tube B, as shown in Fig. 4.

These coin-tubes may be provided with an inscription or mark showing the number of 75 coins they are to contain and the nature of the same.

To prevent the tubes from rolling either during the filling or storing of them, or at other times, I may cause the end plate, a' , of the 80 semi-cylinder A to have a greater diameter than would otherwise be necessary, and I then cut away from such end the part as represented below line $y z$ in Fig. 3, thus leaving the said end with a straight edge, upon which 85 the tube may partly lie during the filling or at other times. Such cut-away portion will also indicate, in place of the before-mentioned hole or slit in the outer tube or in addition thereto, the relative position of the semi-cylinder 90 A when the tube is closed.

What I claim is—

1. In coin-packing boxes, the combination of the cylindrical cover B, having the closed end b, with a semi-cylinder, A, adapted to slide 95 into said cover, and having an end plate, a'' , and a circular end plate, a' , substantially as set forth.

2. The combination of the cylindrical cover B, having the closed end b, with a semi-cylinder 100

der, A, having an inner end plate, a^2 , and an outer circular end plate, a' , of larger diameter than the cylindrical cover, substantially as set forth.

3. The combination of the cylindrical cover B, having the closed end b , with the semi-cylinder A, having an inner end plate, a^2 , and an outer end plate, a' , adapted to project beyond the cylindrical cover, said end plate a' having a straight face or edge, $y z$, substantially as and for the purpose set forth.

4. The combination of a cylindrical cover, B, having the head b , with a semi-cylinder, A, having heads adapted to slide therein, there being a hole in said cover through which the said semi-cylinder or the contents thereof can be viewed, substantially as set forth.

5. The combination, with a semi-cylinder, A, having the circular end a' , and a cylindrical cover, B, adapted to slide onto said semi-cylinder, and having the closed end b , of a capsule C, adapted to be fixed over the end of semi-cylinder A and cover B, substantially as and for the purpose set forth.

In testimony whereof I have signed my name to this specification in the presence of two subscribing witnesses.

ERNST MARTIN HUGO LONITZ.
